UNITED STATES PATENT OFFICE.

MERRILL F. WILCOX, OF BAY CITY, MICHIGAN.

SMOOTHING THE INNER SURFACE OF WOODEN TUBING.

SPECIFICATION forming part of Letters Patent No. 295,703, dated March 25, 1884.

Application filed September 10, 1883. (No model.)

To all whom it may concern:

Be it known that I, MERRILL F. WILCOX, of Bay City, in the county of Bay and State of Michigan, have invented certain new and useful 5 Improvements in the Manufacture of Wooden Pump-Tubing and Pipes, of which the following is a full, clear, and exact description.

This improvement relates to wooden tubing or pipes of different descriptions, but more 10 specially pump-tubing, in which it is desirable to have the "bore" of the tubing as smooth as possible; and it has for its object the production of a smoother and closer interior surface to such tubing than has heretofore been 15 practicable by simply boring it by means of an auger or other like tool. This smoothing I accomplish, not by cutting, but by pressure and friction without removal of the fiber, and for this purpose force along or through the 20 bored hole in the wood a rapidly rotating smooth steel or other suitable plug of slightly larger diameter than the hole or bore. In the advance end of this plug I propose also to form a cavity and charge the same with rosin, 25 gum, or other filling and glazing material, which will be ejected by a centrifugal action from the rapidly rotating plug and caused to fill bad or open places in the wood, as well as to glaze the inner walls of the tubing, and 30 thereby give a smoother or more perfect finish thereto. Such filling and glazing, however, may, if desired, be dispensed with.

Reference is to be had to the accompanying drawings, forming part of this specification, in 35 which similar letters of reference indicate corresponding parts in all the figures.

Figure 1 represents a longitudinal section of a piece of pump-tubing as in the course of having its bore smoothed in accordance with 40 my invention, and with the smoothing-tool as having partially completed its work. Fig. 2 is a transverse section on the line *x* *x* in Fig. 1, and Fig. 3 a transverse section on the line *y* *y* in Fig. 1.

45 A is the wooden tubing, and *b* *b'* its hole or bore, which may be made by an auger, as usual. As the tubing, however, is left by the auger, or before the smoothing-tool is passed through it, its interior walls present a roughened surface, as shown at *b* in Figs. 1 and 2.

To remove the roughness and to give a smooth finish to the interior of the tubing, I take a smooth steel plug, B, or other suitable smooth plug, of six or eight inches in length, more or less, and slightly larger in diameter 55 —say one-sixteenth of an inch, or thereabout—than the hole in the tubing as left by the auger. This plug I run through the bore or auger-hole in the wood, and rapidly rotate the same while passing it along or 60 through the tubing, for which purpose the plug may be screwed into or screwed to the end of a shaft or spindle, C, to which rotary motion and longitudinal feed may be given by any suitable means. This smooths by simple 65 friction and pressure, without detachment or removal of the fiber, the interior walls of the tubing, and gives a hard or close and true cylindrical finish, as at *b'* in Figs. 1 and 3. To give a still smoother and more perfect finish, however, I construct the advance end of the plug with a cavity, *d*, in which is inserted rosin, gum, or other suitable filling and glazing material, *e*, in a pulverized condition. This material will be ejected by centrifugal 70 action during the rotation of the plug, and caused to fill bad or open places in the wood, and as the body of the plug follows in the wake of the cavity *d*, said material will be forced into the interstices or open places in 75 the wood, and the same made to give a fine-glazed finish to the inner walls of the tubing.

Having thus described my invention, what I claim as new, and desire to secure by Letters Patent, is—

1. A method of smoothing the inner surface of wooden tubes, which consists in forcing through said tubes a rapidly rotating smooth steel plug slightly larger than the bore of the tube, as described.

2. A method of filling cavities or open places on the inside of wooden tubes and glazing the inner surface thereof, which consists in centrifugally distributing rosin or like substance on the inner surface in advance of 95 and from a rotary smoother, as described.

MERRILL F. WILCOX.
